UNITED STATES PATENT OFFICE.

JAMES T. DOWDALL, OF GLEN MORRIS, NEW YORK.

SPOOL-HOLDING DEVICE.

Application filed June 16, 1927. Serial No. 199,152.

This invention relates to improvements in spool, tube and cone holding devices adapted to be used with sewing machines, and has for one of its objects the provision of 5 such a device in which the thread may be unwound while sewing, in the same direction that it was originally wound, that is, at right angles to the center line of such spool, tube or cone, and thus avoid any coiling or 10 twisting of the thread, with the resultant added friction on the thread and the tearing thereof.

Another object of the invention is to do away with a wasteful fault common in practically all devices at present in use with power machines, that is, when the thread is drawn from a spool or the like which is centered on a spindle, the thread due to the sudden momentum applied to the spool by 20 the starting or varying speeds of the machine, will drop off in loose circlets about the lower end of the spool and around the spindle as it revolves and will tangle the loose thread, become knotted, tear and often 25 break the needle due to such knotting. The operator in order to clear the tangled thread from the spindle will pull off a quantity of the thread and discard it. This waste in large manufacturing establishments quickly 30 assumes large proportions.

Another object of the invention is to provide a device of this nature in which a spool of thread or the like is frictionally held upon a plug or the like and made to revolve there- 35 with, upon a ball bearing at the lower end thereof, when sewing.

A further object of the invention is to provide a device of this nature in which a threaded spool or the like may be mounted 40 to revolve with the minimum amount of friction.

A still further object of the invention is to provide a spool holding device provided with means to prevent any of the thread from 45 becoming entangled with the spool mounting.

A still further object of the invention is to provide a device of this nature with a spool mounting adapted to be used with spools having different sizes of openings.

50 Other objects and novel features of construction of my improved spool holding device will become apparent as the specification proceeds.

Referring to the drawings, forming a part 55 of this specification, disclosing one embodiment of my invention,

Figure 1 is a view in side elevation of my invention.

Figure 2 is a longitudinal section taken on line 2—2, Fig. 1 and 60

Figure 3 is a top plan view of the ball bearing retaining means.

Referring now to the drawings in detail, 5 indicates a base or support which may be suitably secured to a sewing machine table or the like, and is provided with a substantially U shaped frame 6 secured to, or integral with a bearing post 7 forming a part 65 of the base 5.

The bearing post 7 is provided at the upper end thereof with a cavity 8 (see Fig. 2) having a flat area 9 at the bottom thereof. This cavity 8 with its flat bottom 9 forms a seat or bearing for a ball 10 which is maintained in the said bearing by a bifurcated ball retaining member 11, secured to the post 7 by screws 12. The upper arm 14 of the U shaped frame 6 is provided with an opening 15 through which passes a pin or rod 16 and maintained therein by a pin 17 passing through the upper end of the said rod 16. At the lower end of the said rod 16 there is rotatably mounted a roller 18 which forms an upper guide bearing for a spool 21. A spring 19 bearing against a disk 20 fast to the rod 16 prevents the said rod and roller from accidentally rising out of position. A spool supporting base or disk 25 centrally located on a stud 26 provided with a flat seat ball bearing 27 identical with the cavity 8 in the post 7 forms the lower and main bearing for the spool 21. The spool is frictionally maintained on the stud 26 by means of a spring or resilient member 28 90 therein exerting a tension against the walls of the opening 29 in the spool 21. It will be understood that owing to the spring member 28, it is possible to mount spools having different sizes of openings on the stud 26. After the spool is mounted on the ball 10 and with the roller 18 in proper position, 95

the thread 30 is passed or threaded through a guide member 31 on the frame 6 and then through the eye of the needle. In this position the device is ready for operation. To 100 remove the empty spool, the rod 16 is raised up against the tension of the spring 19 and a full one may be put in place and the rod is then released.

It will be understood, as it is clearly shown 110 on the drawings that the disk 20 does not bear against the spool 21 and the roller 18 is

slightly smaller than the opening 29, thus reducing the friction at this point to a minimum.

It will also be seen that owing to the flat areas 9 and 27 the ball 10 is in contact with only one point on each of these bearings thus reducing the friction at this point to a minimum. It will likewise be seen that the guide member 31 will prevent any loose thread from falling below the bottom thereof and under the spool supporting disk 25. Should more thread than necessary become unwound from the spool when it is rotating in the direction of the arrow (Fig. 1) due to the sudden starting of the sewing machine, the said thread will fall to and contact with the bottom of the guide member 31, said sudden contact will cause the superfluous thread to be rewound on the spool in the opposite direction and when drawn upon will rotate the spool in the opposite direction until the said superfluous thread is used up. A wool, felt or other fibrous material disk 32 under the spool 21 will also tend to prevent any unwound or loose thread from getting under the disk 25. Even if it were possible for any loose thread to get under the disk 25 it could not become entangled thereunder with the stud 26 as the spool 21, disk 25 and the stud 26 revolve together and in the same direction.

It will be seen from the above that I have provided a simple and efficient threaded spool holding device adapted to be used with sewing machines and one that will effectively prevent any tangling or breaking of the thread.

Having described my invention what I claim as new and desire to secure by Letters Patent is:

1. In a spool holding device, a support having a cavity, a ball within the cavity, a

ball retaining bifurcated member on the support, a spool supporting base, a bearing stud in the base upon which the spool is adapted to be frictionally mounted to rotate therewith upon the ball, a frame on the support, and a spool guiding bearing mounted in the frame in line with the bearing stud in the base. 45 50

2. In a device for unwinding thread from a spool having an opening therein, a support having a flat bottom cavity forming a seat for a ball bearing, a ball therein, a spool supporting base, a stud in the base forming a spool mounting, a resilient member on the stud to frictionally engage the interior of the spool opening, a frame on the support, a spool guiding bearing slidably mounted in the frame in line with the stud in the base, the said guiding bearing comprising a rod, a disk fixed to the rod spaced from the spool, a roller of a slightly smaller diameter than the opening in the spool near the lower end of the rod and a spring exerting a pressure against the disk to prevent accidental displacement of the bearing, a flat bottom bearing in the stud resting on the ball, and a thread guide on the frame. 55 60 65

3. In a device for unwinding thread from a spool having an opening therein, a support forming a lower bearing, a ball in the bearing upon which the spool is adapted to be rotatably mounted, a frame on the support, and a spool guiding upper bearing slidably mounted in the frame in line with the lower bearing, the said upper bearing comprising a rod, a disk fixed to the rod spaced from the spool, a roller of a slightly smaller diameter than the opening in the spool near the lower end of the rod, and a spring exerting a pressure against the disk to prevent accidental displacement of the bearing. 70 75 80 85
